STYLUS FOR RECORDERS

George Gorham, New York, N. Y., assignor to
 Technicon Cardiograph Corporation, New
 York, N. Y., a corporation

Application January 11, 1950, Serial No. 137,915

8 Claims. (Cl. 346—139)

1

This invention relates to pens or styluses for recording instruments, and more especially, though not exclusively, for direct-writing electro-cardiographs.

It is the primary object of the present invention to provide a stylus which is of such character that it has a substantially flat frequency response, in that it responds uniformly to all frequencies within the range of frequencies of body voltages in the operation of the electro-cardiograph.

Another object of the present invention is the provision of a stylus of the above character, which is additionally characterized by its simplicity of construction and its reliability in operation.

It is a yet further object of the present invention generally to provide an improved stylus for electro-cardiographs or other recording instruments.

The above and other objects, features and advantages of the present invention will be more fully understood from the following description considered in connection with the accompanying illustrative drawings.

In the drawings:

Fig. 1 is a top plan view of a stylus embodying the present invention;

Figs. 2 and 3 are side elevational and bottom plan views, respectively, of the stylus;

Fig. 4 is an enlarged section taken substantially on the line 4—4 of Fig. 1;

Fig. 5 illustrates perspectively the function of the instant stylus in an electro-cardiograph; and

Fig. 6 is an enlarged section taken on the line 6—6 of Fig. 1.

Referring to the drawings, and more particularly to Figs. 1 to 3 thereof, the reference numeral 10 designates a recording pen or stylus which comprises a blade 12 and a hub 14 on which the latter is mounted in heat-insulated fashion. To this end, the apertured end 20 of the blade 12 is received on a bushing 18 of any suitable heat-insulating material and rests on a preferably integral collar 16 on the latter (Fig. 4). The bushing 18 is, in turn, received on the hub 14 and rests on a preferably integral end collar 32 of the latter. Received on the bushing 18 in superposition on the apertured end 20 of the blade 12 is a spacer 22 which preferably projects above the adjacent end of the bushing 18. The spacer 22 may be made of the same insulating material as the bushing 18. Further received on the hub 14 is a collar 24 which is provided with a set screw 28. The hub 14 has a

tapped hole 30 which is to receive the set screw 28 when the collar 24 is in position to hold the spacer 22, the bushing 18 and the interposed apertured end of the blade 12 securely against the end flange 32 of the hub 14. In the present instance, a pin 34 is driven into the hub 14, the bushing 18, the apertured end 20 of the blade 12, and the spacer 22, in order drivingly to connect these parts. Thus, the blade 12, which during the performance of the instant stylus is heated in a manner and for a purpose hereinafter described, is effectively heat-insulated from the preferably metallic hub 14 and collar 24 by the interposed bushing 18 and spacer 22. The hub 14 serves for mounting the stylus 10 on an oscillatory operating spindle or shaft 36 of a recording instrument, such as an electro-cardiograph. The stylus may conveniently be drivingly connected with the spindle 36 by the same set screw 28 which holds the collar 24 on the hub 14.

The blade 12 is preferably made from one of the metals classified in the metal arts as light metals, such as magnesium, aluminum, beryllium, copper and others. A presently preferred blade 25 is made of a magnesium alloy of the kind identified by Dow Chemical Co. as FS1 annealed, and consisting of 95.7% magnesium, 3% aluminum, 1% zinc and 0.3% manganese. The blade 12 is at its recording end 38 preferably reduced widthwise to form a tip with which legibly to record an electro-cardiogram on a web W of recording material (Fig. 5) in an electro-cardiograph of the direct-writing type, for instance. Accordingly, the blade 12 is heated so that its recording end 30 or tip 38 will leave a visual record directly on the recording web W. The web W may, to this end, be chemically treated paper of a known type on which the visual record is produced when being subjected to the heat of the contacting recording tip 38 of the stylus in the fashion shown in Fig. 5, while the web W is being moved longitudinally in the direction of the arrow A over the narrow edge 42 of a support or anvil 44 in a manner more fully disclosed in my co-pending applications Ser. No. 762,613, filed July 22, 1947, Ser. No. 788,801, filed November 29, 1947, now Pat. No. 2,524,564, issued October 3, 1950, and Ser. No. 74,668, filed February 4, 1949. In order to heat the recording end or tip 38 of the stylus, there is provided on the blade 12, and preferably wound directly on a portion of the recording tip 38 itself, an electric heating coil 50 which has preferably integral leads 52 and 54 that extend rearwardly along the blade 12 to the spacer 22 where they are connected with wires 56 and 58,

respectively, which are, in turn, connected with any suitable electric source.

The recording material used in direct-writing electro-cardiographs is blushed lacquer-coated paper or other heat-sensitive record material, which has lines printed thereon to facilitate the accurate study of an electro-cardiogram recorded thereon. It has been found that when the stylus is used for recording on the printed surface of certain paper, comparatively rapid wear of the recording tip of the stylus takes place, manifesting itself in ridges or grooves in the tip of the stylus on the surface thereof next to the pointed edge of the anvil or platen 44, thus impairing the character of the trace formed on the paper. To overcome this objection, the recording end or tip 38 of the instant stylus 10 is, as best shown in Fig. 6, provided with a wrapper 40 of any suitable chemically inert material which is not affected by the printing material with which the lines on the recording web are formed. A satisfactory wrapper material for this purpose is platinum foil, for instance. The wrapper 40 may conveniently be held securely on the recording stylus end 38 in any suitable way as by the heating coil 50 which is wound around the adjacent length of the wrapper 40. Of course, the wrapper 40 may be dispensed with if the instant stylus is used on record material which does not adversely affect the stylus.

To further carry out the objective of a light-weight stylus, the heating coil 50 and its leads 52 and 54 are preferably made from a length of light-gauge wire which is preferably glass coated for electrical insulation, or otherwise coated with suitable insulation material which safely withstands the heat emanating from coil 50. Wire known to the trade as "Nichrome" has been found suitable for said heating coil. The leads 52 and 54 of the heating coil 50 are preferably passed from one side to the opposite side of the blade 12 through holes 60 and 62 therein, respectively, and are electrically connected with the wires 56 and 58 in metal eyelets 64 and 66, respectively, in which they are secured by solder or in any other suitable way.

The eyelets 64 and 66 are provided in the spacer 22 (Fig. 4), and the material from which the latter is made is preferably also electrically insulating as is also member 16. The metallic blade 12 is provided with further holes 68 and 70 in order to clear the metallic eyelets 64 and 66, respectively. The blade 12, being made of minimum thickness in accordance with the objective of obtaining a stylus of minimum weight, is preferably reinforced by an impressed longitudinal ridge or bead 14.

The instant stylus 10 is characteristic for its simple yet sturdy construction, and especially for its light weight which renders it so uniformly responsive to all frequencies within the range of frequencies of body voltages in the operation of an electro-cardiograph, for instance. In addition to the light weight of the blade 12 itself, the fine wire of the heating coil 50 and the rearward extension of the equally fine wire leads 52 and 54 of the latter to the eyelets or terminals 64 and 66, respectively, further aid in reducing the weight of the instant stylus to a minimum. The passage of the relatively long leads 52 and 54 of the heating coil 50 through the holes 60 and 62, respectively, in the blade 12 substantially midway thereof effectively prevents these leads from displacement sidewise on the oscillating stylus.

While I have shown and described the preferred embodiment of my invention, it will be understood that various changes may be made in the present invention without departing from the underlying idea or principles of the invention within the scope of the appended claims.

Having thus described my invention, what I claim and desire to secure by Letters Patent is:

1. A stylus for making a record on heat-sensitive recording material, comprising a metallic blade having a recording end and an opposite apertured end, a metallic hub having a collar at one end, a sleeve of heat-insulating material surrounding said hub and having an end collar resting against said hub collar, said apertured blade end being received by said sleeve and resting against the collar of the latter, a spacer of electrical-and-heat insulating material received by said sleeve and overlying said apertured blade end, a collar secured to said hub and engaging said spacer to hold the latter in firm engagement with said apertured blade end, a driving connection between said apertured blade end and said hub, an electric heating coil electrically insulatingly mounted on, and in heat-exchange relation with, said blade near the recording end thereof, spaced metallic eyelets mounted in said spacer above said apertured blade end, electrically insulated leads extending from the ends of said coil into said eyelets, respectively, and current-supply wires leading into said eyelets, respectively, the ends of said leads and wires in said eyelets, respectively, being electrically connected, and said blade being provided with apertures to clear the adjacent eyelets, respectively.

2. A recording stylus as set forth in claim 1, in which said leads and wires in said eyelets, respectively, are anchored in the latter and permanently held electrically connected by solder in the respective eyelets.

3. A stylus for making a record on heat-sensitive recording material, comprising a metallic blade having a recording end and an opposite apertured end, means associated with said blade adjacent said apertured end for mounting said blade for oscillation in its own plane, said means including a member formed of electrical-and-heat insulating material overlying said apertured blade end, an electric heating coil electrically insulatingly mounted on, and in heat-exchange relation with, said blade near the recording end thereof, spaced metallic eyelets mounted in said member above said apertured blade end, electrically insulated leads extending from the ends of said coil into said eyelets, respectively, and current-supply wires leading into said eyelets, respectively, the ends of said leads and wires in said eyelets, respectively, being electrically connected, and said blade being provided with apertures to clear the adjacent eyelets, respectively.

4. A stylus, as defined in claim 3, wherein said recording end is constituted by a recording tip formed by a widthwise reduced end length of the blade so as to provide a shoulder between said tip and the remainder of said blade, and said coil surrounds a length of said tip and bears against said shoulder.

5. A stylus, as defined in claim 4, wherein said tip is provided with a protective coat of heat-conductive material which is chemically inert to the recording material.

6. A stylus, as defined in claim 5, wherein said chemically inert protective coat comprises a platinum foil wrapper on said tip.

7. A stylus for making a record on heat-sensitive recording material, comprising an elongated unitary metallic blade having a recording end and an opposite apertured end, means associated with said blade adjacent said apertured end for mounting said blade for oscillation in its own plane, said means including a member formed of electrical-and-heat insulating material overlying said apertured blade end, an electric heating coil electrically insulatingly mounted on, and in heat-exchange relation with, said blade near the recording end thereof, electrically insulated leads extending from the ends of said coil, current-supply wires electrically connected to the ends of said leads, respectively, and means to insulatingly secure said lead ends and said current supply wires to said blade adjacent said apertured blade end, said recording end of the blade being formed by a widthwise reduced end length of the latter so as to provide a shoulder between said end length and the remainder of said blade, and said coil surrounding a portion of said end length and bearing against said shoulder.

8. A stylus for making a record on heat-sensitive record material comprising an elongated uni-

tary metallic blade having an intermediate shank, a flat recording tip formed at one end of the shank by a widthwise reduced end length of the blade and a blade mounting part formed at the other end of the shank to mount the blade for oscillation in its own plane, an electric heating coil surrounding said tip and spaced inwardly from the free end of the tip, electrically insulated leads extending from the ends of said coil longitudinally of said shank, and means to insulatingly secure said leads to said blade mounting part, said tip having a shoulder and said coil bearing against said shoulder.
